(57) **CLAIM**

The ornamental design for a collapsible cart, as shown and described.

DESCRIPTION

FIG. 1 is a perspective view of a collapsible cart of the present invention;

FIG. 2 is a right side view of the collapsible cart;

FIG. 3 is a left side view of the collapsible cart;

FIG. 4 is a front view of the collapsible cart;

FIG. 5 is a back view of the collapsible cart;

FIG. 6 is a top view of the collapsible cart; and,

FIG. 7 is a bottom view of the collapsible cart.

The broken lines shown in the drawings illustrate portions of the collapsible cart that form no part of the claimed design.
